UNITED STATES PATENT OFFICE.

HERMAN C. ORCHARD, OF ST. LOUIS, MISSOURI, ASSIGNOR TO ORCHARD PAPER COMPANY, OF ST. LOUIS, MISSOURI, A CORPORATION OF MISSOURI.

METHOD OF PRODUCING CONFIGURED PAPER.

Application filed February 18, 1922. Serial No. 537,406.

To all whom it may concern:

Be it known that I, HERMAN C. ORCHARD, a citizen of the United States, residing at the city of St. Louis, in the State of Missouri, 5 have invented certain new and useful Improvements in Methods of Producing Configured Paper, of which the following is a specification.

This invention consists of a new article 10 of manufacture, viz., an article composed of paper or similar material having configurations imprinted therein neither by watermarking nor by ordinary printing with ink. This invention, furthermore, consists in the 15 method to be used in imparting such markings or configurations to the said material and the formula of ingredients to form the bath used in such method.

In the accompanying drawings forming 20 part of this specification, in which like numbers of reference denote like parts wherever they occur,

Figure 1 is a diagrammatic side elevation; Figure 2 is a perspective view of a 25 configuring roll, broken away; and

Figure 3 is a fragment of configured paper imprinted by means of the use of this invention.

The tank 1, of any suitable or desired 30 size, shape, or arrangement, contains liquid 2, adapted when brought into contact with paper (or similar material) 3 to impart to it the replica of configuration 4, or any configuration, found intaglio on roll 5.

35 Roll 6 revolves in liquid 2, being driven by shaft 7 in any preferred manner, and causes liquid 2 to come into contact with the face of roll 5, revolubly mounted on or with shaft 8. A doctor or scraper 9, 40 of any desired construction, lies close to the surface of roll 5 and removes surplus liquid 2 therefrom. Means for longitudinal reciprocation of the doctor 9 is not shown in the drawings, but it should be understood that such operation is preferable, in order 45 to prevent wearing grooves in the engraved surface 4 of roll 5.

The paper 3 travels, in the direction indicated by the arrows, between roll 5 and the 50 printing drum or roll 10, so mounted as to rotate on or with shaft 11, and receives the imprint or impression of the liquid 2 lying in the grooves or channels or intaglio depressions forming the design 4 on roll 5. 55 The result of this contact is the production

on paper 3 of a pattern, design, or configuration, as appears in Figure 3, that is a counterpart or reproduction of that engraved at 4 on roll 5.

The configuration thus imparted to the 60 paper 3 is not such as is produced by the ordinary intaglio printing process or by the well-known watermarking process. The method used in this invention is much 65 cheaper than either of those processes, and is performed when the paper 3 is dry, as distinguished from the wet condition of the paper when the ordinary watermarking process is practiced. This invention is distinguished from ordinary printing with ink 70 by the fact that no surface adhesions are left on the paper.

The product produced by this invention 75 is much more elegant than a sheet printed with ink, its configuration somewhat resembling a watermark in appearance; but whereas, a watermark is always lighter in color than the surrounding material, the configuration of this invention consists of parts darker than the adjacent material. 80 Another noteworthy difference between this invention and a watermark is that watermarks are nearly always blurred, cloudy, unclear, faint, and illegible. The mark produced by this invention is clear, vivid, and 85 legible, and its edges are not blurred. On the contrary, this invention makes it possible to impart a design containing fine lines or ornaments, which design can be readily seen in the paper and without holding it up to the light like a watermark, and every part and feature of such design can be distinctly seen, even if it contains the finest tracery. Yet it looks like it is in the 90 paper like a watermark, and does not resemble ink-printing.

The result is a paper of a great elegance and cheapness, adapted for wrapping candy, cakes, and fine articles of women's apparel or anything else that will appear to better 100 advantage in a dainty wrapping. It can be used, also, as the lining of boxes or packages intended for such recherché use.

Because of the distinctness with which the 105 design produced by this invention can be seen in the material, the name and address of the tradesman can be impressed in the paper or the like instead of, or in addition to, the ornamental configuration, or some other advertisement can be used in it. The 110

ornamental design may cover all or any part of a given area of paper and may be of any pattern.

In sum, this imprint looks like a water-mark, but is more distinct, and extends within one surface of the paper a sufficient distance so that it can be seen through the paper on either side, and is produced while the paper is dry and not by the old water-marking process, but by one much cheaper and quite different and which is differentiated from ink-printing by the fact that the liquid 2 enters the pores or interstices of the paper and leaves no surface adhesions of material, like the ink in printing. This invention causes the imprinted side of the paper to have a glossy or shiny appearance, but does not leave the paper either greasy or sticky.

The liquid 2 is preferably composed of a mixture of rosin dissolved in naptha, gasoline, or other mineral oil or with xilo or similar material. It is thinned with the naptha or similar liquid till its consistency is such that it is quite fluid in tank 1 and stops easily on roll 5 and prints with facility on paper 3 from the intaglio part or depressed engraving 4 on roll 5. The consistency of liquid 2 will, by thinning with naptha or the like, be materially more fluid than, for example, gloss oil, which is a material used in print shops to mix with the ink to make the ink dry quicker.

The consistency of liquid 2 will be such

that it will readily impregnate the surface 35 of the paper 3 to which it is applied. In most cases, it will be applied to one side or surface only of paper 3, but may be applied to both surfaces.

Having thus described this invention, I 40 hereby reserve the benefit of all changes in form, arrangement, order, or use of parts, as it is evident that many minor changes may be made therein without departing from the spirit of this invention or the scope 45 of the following claims.

I claim:

1. The herein-described method of producing sheet paper marked with a visible configuration immediately within one of its 50 surfaces and visible on both sides of the sheet without light passing therethrough, consisting in imprinting on one surface of the paper a liquid containing mineral oil mixed with rosin.

2. The herein-described method of producing sheet paper having non-blurring marks therein resembling watermarks visible on both sides of the sheet without intercepting the latter between light and vision, consisting in imprinting on one surface of the sheet, when dry, a liquid containing mineral oil mixed with rosin, the said liquid being of a decided fluid consistency.

In testimony whereof I hereunto affix my 65 signature.

HERMAN C. ORCHARD.
